[57] CLAIM

The ornamental design for a pair of construction belt suspenders, as shown and described.

DESCRIPTION

FIG. 1 is a front elevational view of a pair of suspenders showing my new design;

FIG. 2 is a front perspective view thereof; and,

FIG. 3 is a back perspective view thereof.

The broken line showing of the human form, belt, hammer, and pocket in FIG. 1 is for illustrative purposes only and forms no part of the claimed design.
